UNITED STATES PATENT OFFICE

DOROTHY LONG, OF NEW YORK, N. Y., ASSIGNOR TO FRANKLIN SIMON & COMPANY, INC., OF NEW YORK, N. Y., A CORPORATION OF NEW YORK

DESIGN FOR A DRESS

Application filed April 20, 1929. Serial No. 30,960. Term of patent 3½ years.

To all whom it may concern:

Be it known that I, DOROTHY LONG, a citizen of the United States, and a resident of the city of New York, borough of Manhattan, in the county of New York and State of New York, have invented the new, original, and ornamental Design for Dress, of which the following is a specification.

Reference is had to the accompanying drawing, forming part thereof, wherein

my new design, the same being illustrated on a figure indicated by dotted lines;

I claim:—

The ornamental design for a dress substantially as shown and described.

Signed at New York, in the county of New York and State of New York, this 18th day of April, A. D. 1929.

DOROTHY LONG.
